UNITED STATES PATENT OFFICE.

WILLIAM M. ROBERTS, JR., OF CUMBERLAND, MARYLAND.

TRACK-CLEANER OR CURRENT-COLLECTOR.

SPECIFICATION forming part of Letters Patent No. 570,839, dated October 27, 1896.

Application filed January 27, 1896. Serial No. 577,073. (No model.)

To all whom it may concern:

Be it known that I, WILLIAM MILNOR ROBERTS, Jr., a citizen of the United States, residing at Cumberland, in the county of Allegany and State of Maryland, have invented certain new and useful Improvements in Track-Cleaners or Current-Collectors; and I do hereby declare the following to be a full, clear, and exact description of the invention, such as will enable others skilled in the art to which it appertains to make and use the same.

My invention relates to improvements in track-cleaners or current-collectors for street-railways; and it consists in certain novel features herein described and claimed.

Reference is had to the accompanying drawings, in which the same parts are indicated by the same letters throughout the several views.

Figure 1 represents an end view of a portion of the truck of a street-car, showing the track-cleaning brush in the operative position. Fig. 2 is a similar view showing the brush on the opposite side of the car raised out of engagement with the track. Fig. 3 is a detail view showing the brush, and showing the holding-sleeve in section. Fig. 4 represents a section along the line 4 4 of Fig. 3. Fig. 5 represents a section along the line 5 5 of Fig. 1 and looking down.

A represents the wheel-guard, to which the brush-holding attachments are secured, but these attachments may be supported by any part of the truck or the framework thereof, or connected to the bottom of the car in any convenient way.

B represents one of the wheels, and C one of the track-rails.

D represents the brush, which is secured in the metal plate D', having a sleeve d, internally screw-threaded, as shown in Fig. 4. This brush and plate and sleeve are of the ordinary manufacture and are not separately claimed as part of my invention. Screwed into this sleeve d is a short pipe or casing E, preferably gas-pipe, screw-threaded, as at e, and provided with vertical slots e' on opposite sides thereof, terminating in horizontal slots e'', having downwardly-projecting holding-lips e'', showing a construction similar to that commonly known as a "bayonet-joint." Extending through these slots e' is a pin F, which

is normally pressed upward by a spring G, interposed under pressure between the pin F and the plate D', as shown in Fig. 4. This 55 pin F may be secured to any fixed part of the framework of the car immediately over the track-rails, but is preferably secured in the sleeve H, inclosing the pipe E, in which said pipe E is free to move vertically. This sleeve 60 H is preferably provided with a screw-cap H' to keep out snow, dirt, and other matter likely to affect the operation of the parts inclosed in the casing E and in the sleeve H. It will be obvious that a single slot or groove 65 on one side only of the casing may be used instead of two slots, and that the pin F may only project part of the way into the casing.

The sleeve H is adjustably held in a bracket K, secured either to the wheel-guard A or to any other suitable part of the car. This bracket K is provided with a sleeve k, adapted to receive the sleeve H, which is clamped therein by the clamp-screw k'. This bracket is secured in place by means of bolts k' or in 75 any other convenient way.

The brush is shown in the operative position in Figs. 1 and 3, in which the spring G presses the brush down to the limit of its downward travel, the said brush being then 80 held against further downward travel by the pin F, while the spring G keeps the brush pressed downward firmly on the track. When it is desired to remove the brush from contact with the track for any reason, pull up on 85 the brush until the pin F is below the holding-lip e'', and then by giving a partial revolution to the brush, preferably about ninety degrees, the pin F will pass into the horizontal slot e'', and when the brush is released it 90 will be pressed downward and the pin F will be locked in the curved recess behind the holding-lip e'', and thus in a simple and expeditious manner the brush may be thrown out of engagement. To throw the brush back 95 in an engagement with the track, lift up on the brush sufficient to clear the holding-lip e'', turn the brush through the reverse angle, and let go of it, and the spring G will press it down on the track.

The spring G will enable the casing E to rise and fall in the guide-sleeve H, and thus the brush D will accommodate itself to irregularities in small obstructions on the track.

As these brushes wear out on the ends the clamp-screw k^o should be unscrewed and the sleeve II lowered a sufficient distance and clamped again in position. In this way, with 5 the herein-described device, a brush may be continuously used until it is worn out and the brush may be at all times readily adjusted for wear.

It will be seen that the operating-spring is 10 held in and protected by the casing, and there is a compact arrangement of parts that may readily be assembled and as readily separated, and that the parts liable to injury or clogging up are well protected.

15 The herein-described device may also be used for holding sliding contacts for making electrical connection and for kindred purposes.

It will be obvious that various modifications 20 of the herein-described apparatus might be made which could be used without departing from the spirit of my invention.

Having thus described my invention, what I claim, and desire to secure by Letters Patent 25 of the United States, is—

1. In a track-cleaner or current-collector, the combination with a brush and a hollow casing secured to the back thereof, and provided with a longitudinal slot extending along 30 one side of said casing and a lateral slot connected therewith, of a pin fastened to the car and projecting into said slot, a spring held under pressure between said pin and the back of said brush, and a guide for said casing adapted to permit the vertical movement 35 thereof, substantially as described.

2. In a track-cleaner or current-collector, the combination with a brush and hollow casing secured to the back thereof and provided 40 with a longitudinal slot extending along one side of said casing and a lateral slot connected therewith, of a pin fastened to the car and projecting into said slot, a spring inclosed in 45 said casing and held between said brush and said pin, and a guide for said hollow casing adapted to permit the motion thereof in a vertical direction, substantially as described.

3. In a track-cleaner or current-collector, the combination with a brush and a hollow 50 casing secured to the back thereof, and provided with a longitudinal slot extending along one side of said casing and a lateral slot connected therewith, of a sleeve inclosing said casing, and permitting a vertical play of said casing therein, a pin fastened to the sleeve and projecting through 55 said casing and into said slot, and a spring held under pressure between said pin and the back of said brush, substantially as described.

60 4. In a track-cleaner, the combination with a brush and a hollow casing secured to the back thereof, and provided with a longitudinal slot extending along one side of said casing and a lateral slot connected therewith,

of a sleeve inclosing said casing, and permitting a vertical play of said casing therein, 65 means for adjusting the position of said sleeve relative to the track, a pin fastened to the sleeve and projecting into said slot, and a spring held under pressure between said pin and the back of said brush, substantially as described.

5. In a track-cleaner, the combination with a brush and a hollow casing secured to the back thereof, and provided with a longitudinal slot 70 extending along one side of said casing and a lateral slot connected therewith, of a sleeve inclosing said casing, and permitting a vertical play of said casing therein, a bracket adapted to hold said sleeve; means for adjustably securing said sleeve in said bracket, a pin fastened to the sleeve and projecting into said slot, and a spring held under pressure between said pin and the back of said brush, substantially as described. 75

6. In a track-cleaner, the combination with a brush and a hollow casing secured to the back thereof, and provided with oppositely-disposed longitudinal slots extending along 80 opposite sides of said casing and lateral slots connected with said longitudinal slots, of a pin fastened to the car and projecting through said casing and into said slots, a spring held under pressure between said pin and said brush, and a guide for said casing adapted 85 to permit the vertical movement thereof, substantially as described.

7. In a track-cleaner, the combination with a brush and hollow casing secured to the back thereof and provided with oppositely-disposed longitudinal slots extending along 90 opposite sides of said casing and lateral slots connected with said longitudinal slots, of a pin fastened to the car and projecting through said casing and into said slots, a spring inclosed in 95 said casing and held between said brush and said pin, and a guide for said hollow casing adapted to permit said casing to move in a vertical direction, substantially as described. 100

8. In a track-cleaner, the combination with a brush and a hollow cylindrical casing secured to the back thereof, and provided with longitudinal slots extending along the opposite sides of said casing and lateral slots connected with said longitudinal slots, of a sleeve inclosing said casing, and permitting a vertical play of said casing therein, a pin fastened to the sleeve and projecting through 115 said casing and into said slots, and a spring held under pressure between said pin and said brush, substantially as described. 120

In testimony whereof I affix my signature in presence of two witnesses.
